UNITED STATES PATENT OFFICE.

PERLEY C. CLARK, OF MONTROSE, COLORADO.

HYDRANT.

Application filed November 24, 1924. Serial No. 752,053.

To all whom it may concern:

Be it known that I, PERLEY C. CLARK, a citizen of the United States, and a resident of Montrose, in the county of Montrose and State of Colorado, have made certain new and useful Improvements in Hydrants, of which the following is a specification.

This invention relates to an improvement in hydrants and aims to provide a hydrant which is of simple and durable construction, which is easy, reliable and noiseless in operation, which may be easily taken apart for purposes of replacement and repair and as easily assembled, which may be readily opened or turned on, and which closes automatically without shock or jar, unless set to be held open and which is comparatively inexpensive to manufacture and install.

A further object is the provision of a hydrant wherein the delivery or discharge pipe of the valve casing is vented automatically when the hydrant is closed, although escape of water through the vent is prevented when the hydrant is open.

Other objects and advantages reside in certain novel features of the construction, arrangement and combination of parts which will hereinafter be more fully described and particularly pointed out in the appended claims, reference being had to the accompanying drawings forming a part of this specification, and in which:—

Figure 1 is a view partly in elevation and partly in section showing a hydrant constructed in accordance with the present invention;

Figure 2 is a view partly in central longitudinal section and partly in elevation showing the hydrant proper when in closed position;

Figure 3 is a view in central longitudinal section showing the hydrant proper when held in open position;

Figure 4 is a fragmentary perspective view of the lower end of the delivery pipe showing the valve of the vent detached;

Figure 5 is a fragmentary detail view in elevation showing one way of connecting the coil spring to the delivery pipe;

Figure 6 is a view in section on the line 6—6 of Figure 2;

Figure 7 is a similar view on line 7—7 of Fig. 3;

Figure 8 is a detail perspective view showing one set of co-acting lugs,

Figure 9 is a view in elevation showing a

lever and chain operating mechanism and a hose connection organized with the discharge end of the delivery pipe.

Figure 10 is a fragmentary view in elevation showing a modified form of discharge spout,

Figure 11 is a detail perspective view of the bracket plate for the lever of the arrangement shown in Fig. 9, and

Figure 12 is a view in section on the line 12—12 of Fig. 9.

Referring to the drawings and more particularly to Figs. 1 to 3, inclusive, the numeral 10 designates the water supply pipe which is disposed below the front line and which carries the water under pressure to a fitting or T-connection 11 threaded on to one end of the water supply pipe and located in a hydrant box 12. One horizontal branch of the T is threaded on to the water supply pipe as stated and the other horizontal branch of the T is plugged as at 13. The vertically arranged branch of the T has the lower end of a valve casing 14 threaded thereinto, as indicated at 15.

On the lower end of the valve casing 14 a partition 16 is integrally formed. A stuffing box or packing gland 17 is provided on the upper end of the valve casing 14.

A single piece delivery pipe 18 has its lower end slidably and rotatably fitted in the valve casing 14, the delivery pipe being packed by the stuffing box or gland 17. The lower end of the delivery pipe 18 is closed, as at 19, and just above the closed end 19 ports 20 are provided at spaced intervals around the periphery of the delivery pipe. These ports 20 may be positioned within the valve casing 14 and above the ported partition 16 in the closed position of the hydrant, as shown in Figure 2, but also may be located below the ported partition 16 and in open communication with the water supply in the open position of the hydrant, as shown in Figure 3, all of which will hereinafter more clearly appear. A valve 21 which comprises a disk of rubber or other yieldable material is carried by the lower closed end 19 of the delivery pipe, the valve disk being secured in position by means of a screw 22 and washer 23, the screw extending through the washer and through the valve disk and being threaded into the closed ends 19 of the delivery pipe. The valve disk 21 is of greater diameter than the delivery pipe and a portion of this valve disk projects beyond

the lower end of the delivery pipe and is adapted to engage against the underside of the ported partition 16, as illustrated in Figure 2, in order to effectively seal the interstice between the delivery pipe and the ported partition, thereby preventing water from seeping from the water supply pipe and connection 11 into the valve casing 14 when the hydrant is closed or turned off.

10 For the purpose of facilitating manipulation of the delivery pipe and also for the purpose of providing a discharge spout, the upper end of the delivery pipe 18 is curved around and downwardly to provide a substantially U-shaped upper end 25 which may be conveniently gripped or pressed to push the delivery pipe 18 downwardly or to turn the same angularly as may be necessary to effect a proper adjustment and manipulation of the hydrant.

Oppositely disposed pairs of lugs are provided on the valve casing and on the portion of the delivery pipe located within the valve casing, the lugs of the valve casing being designated at 26 and lugs of the delivery pipe being designated at 27. As illustrated to advantage in Figures 6, 7 and 8, the lugs of the delivery pipe and valve casing are substantially L-shaped in the construction shown and are designed to have their horizontally projecting portions 26^a and 27^a interengaged when the delivery pipe has been depressed to position the ports 19 below the partition 16 and the delivery pipe has been turned in this lower portion to bring these horizontally extending portions 26^a and 27^a into vertical alinement. When the lugs 26 and 27 are engaged they serve to hold the delivery pipe in open position so that a continuous flow of water is had without the necessity of holding the delivery pipe down.

40 These lugs also provide means whereby the delivery pipe may be used to assemble and disassemble the valve casing 14 with the T 11.

50 A compression or torsional coil spring 30 encircles the delivery pipe and has one end fastened as at 31 to the nut of the packing gland 17. The other end of the coil spring is fastened as at 32 to a clamp 33 adjustably but rigidly fixed on the delivery pipe. The spring 30 biases the delivery pipe to such position as to close the valve 21 and to position the lugs 26 and 27 so that they will 55 not engage each other. Of course it is to be understood that the lugs 26 and 27 are spaced from each other angularly so that they do not interfere with vertical movements of the delivery pipe unless the delivery pipe is turned to interengage the lugs.

60 As shown in Figures 2, 3 and 4, a collar 35 is integrally formed with or suitably fixed to delivery pipe and is designed to fit up against the packing of the gland or packing box 17 when the hydrant is closed (see Fig.

2). This collar 35 has a snug working fit in the valve casing but has not a fluid tight fit therein although passage of fluid between the collar and the valve casing is resisted and retarded.

70 The valve casing 14 is provided with a vent 36^a which is designed to permit the escape of the water from the delivery pipe and from the valve casing when the hydrant is turned off and the valve 21 is seated or closed. In order to prevent the escape of water when the hydrant is turned on and the valve 21 is opened, a valve plate 36 is provided and has its upper end received within a groove 37 provided in the collar 35 so that the upper portion of the valve plate 36 will be countersunk in the collar. The valve plate 36 has an angular extent somewhat greater than the groove 37 and has notches 38 which accommodate the portions of the collar 35 at the ends of the grooves 37. The lug 27 which the valve plate 36 overlies is also cut away, as at 39, and recessed, as at 40, for the purpose of accommodating the valve plate and for permitting escape of water when the hydrant is turned off.

75 In operation when the curved upper end 25 of delivery pipe is depressed the delivery pipe moves downwardly until the ports 20 are positioned below the partition 16 as shown in Figure 2 whereupon water flows from the water supply pipe tank 10 and the T 11 through the ports 20 and into the delivery pipe 18. The water of course issues from the downwardly turned outlet end of the delivery pipe. If it is desired to keep the water turned on for any length of time the delivery pipe 18 is not only pressed downwardly but is rotated after having been pressed downwardly for the purpose of bringing the lugs 26 and 27 into engagement. When the lugs 26 and 27 are engaged the delivery pipe is held in open position as shown in Figure 3. When it is desired to close the valve 21 and shut off the supply of water, the delivery pipe is turned so as to disengage the lugs 26 and 27 and the spring 30 turns the delivery pipe to the position shown in Figure 2. The spring 30 is shown as having a light torsional action so as to assist in disengaging the lugs, but if desired, and as shown in Fig. 9, this spring 30 may consist of an ordinary compression spring which is simply interposed between the packing nut 17 and a suitable abutment of the delivery pipe and which is not held or positively connected to either. The return of the delivery pipe to closed position is retarded to prevent shocks and jars and to eliminate noises and this retarding action results from the fact that the water in the space 50 above the collar 35 in the position of the parts shown in Fig. 3 can escape past the collar 35 only very slowly,

since the collar 35 has a snug working fit in the valve casing and since there is only a very small interstice between the periphery of the collar and the inner wall of the valve casing. Of course, it is to be understood that water from the supply pipe 10 and fitting or connection 11 works up into the space 50 when the hydrant is running and in the position shown in Fig. 3. The plate valve 36 prevents the escape of water through the vent 36^a when water is running from the hydrant for this plate valve covers the port 36^a at such time. However, when the water is shut off and the parts are positioned as shown in Fig. 2, the plate valve is above the vent 36^a and the vent serves to drain the water from the delivery pipe 18 and the valve casing 14.

Referring to Figures 9 to 12 inclusive it will be seen that in lieu of providing a substantially U-shaped upper end such as is shown at 25 in Figures 1, 2 and 3, a hose connection 50 may be threadedly engaged with the upper end of the street delivery pipe (see Fig. 9). If a hose connection is not desired a discharge fitting, such as is indicated at 51 in Fig. 10, may be applied to the upper end of the street delivery pipe. The hydrant shown in Figs. 9 to 12, inclusive, is illustrated as being operated by a lever 52 having a bifurcated end 53 which embraces a bracket 54 secured on the pipe 18 by a clamp 55. A pivot bolt 56 extends through openings provided in the arms 53^a of the bifurcated end of the lever and through an opening provided therefor in the bracket 54. A nut 57 holds the pivot bolt against displacement. The pivot bolt serves to pivotally connect the lever 52 on the bracket 54. A chain 58 is connected to the bifurcated end of the lever, a link of the chain being fitted between the arms 53^a, as shown in Figure 12, and being secured to these arms by means of a bolt 59 which extends through openings provided in the arms and through the link disposed between the arms. A nut 60 holds the bolt 59 against displacement. As will be understood from the drawing it is the upper end of the chain 58 which is connected to the lever and the lower end of the chain is connected, as at 61, with a clamp 62 secured to the valve casing 14. The arrangement of the clamp 62 on the valve casing is merely for the purpose

of fixing the lower end of the chain and of course the lower end of the chain may be otherwise suitably secured or anchored.

With the arrangement shown when the lever 52 is depressed the chain 58 will be drawn taut and the pipe 18 will be pushed downwardly, the lever being fulcrumed on the chain and being connected with the pipe 18 through the bracket 54. The bracket 54 is cut away or slotted, as at 65, to accommodate the pivot bolt 59 and the chain 58.

I claim:

1. In a hydrant, a water supply pipe, a connection coupled to the water supply pipe, a valve casing screwed into the connection, a delivery pipe having a portion within the valve casing, and interengaging means between the delivery pipe and valve casing whereby the valve casing may be assembled with the connection or disassembled therefrom by manipulation of the delivery pipe and whereby the valve may be releasably and positively held in open position.

2. In a hydrant, a water supply pipe, a valve casing connected with the water supply pipe and having a ported partition open on its lower side to the water supply pipe, a delivery pipe having its lower end slidably fitted in the valve casing and in the ported partition thereof, the lower end of the delivery pipe being closed, said delivery pipe having ports adjacent its lower end affording communication between the water supply pipe and the delivery pipe when the ports are positioned below the ported partition, a valve carried by the lower end of the delivery pipe and co-operable with the ported partition, and interengageable lugs carried by the casing and the delivery pipe whereby the delivery pipe may be held in position by said lugs to maintain the valve open.

3. In a hydrant, a valve casing, a delivery pipe slidably and rotatably fitted in said casing, a valve carried by the delivery pipe and co-operable with the valve casing, oppositely disposed L-shaped lugs carried by the valve casing and delivery pipe to hold the delivery pipe in such position as to maintain the valve open by virtue of interengagement of the lugs, and a spring co-operable with the delivery pipe and tending to urge the same to such position as to close the valve.

PERLEY C. CLARK.
